UNITED STATES PATENT OFFICE.

ANDREW SNOW, JR., OF NEW BEDFORD, MASSACHUSETTS.

DESIGN FOR A GLASS RECEPTACLE.

SPECIFICATION forming part of Design No. 35,062, dated September 10, 1901.

Application filed July 27, 1901. Serial No. 69,996. Term of patent 3½ years.

To all whom it may concern:

Be it known that I, ANDREW SNOW, Jr., of New Bedford, in the county of Bristol and State of Massachusetts, have invented and produced a new and original Design for a Glass Receptacle, of which the following is a specification, reference being had to the accompanying drawings, in which—

Figure 1 represents a side view; Fig. 2, a diametrical vertical section of Fig. 1, and Fig. 3 is a fragmentary horizontal section at the point *a* and *y* in Fig. 2.

The leading feature of my design consists of prism-like ribs extending from at or near the bottom of the receptacle toward the top and a row of smooth-surfaced concavities at or near the top or edge.

A indicates the body of the receptacle. The upper edge is indicated with lobes of different sizes, forming a series of points *c c*, which are arched, having at the base of each arch points *d* of larger size. Below the edge is a row of smooth circular depressions *a a*,

commonly called "punties" or "bull's-eyes." Below the row of punties are projections *b b*, 25 with faces in the form of prisms. Between each prism is a smooth-faced depression *f*. In Fig. 3 the formation at *y y* and *x x* in Fig. 2 is shown. Above and below the series of prisms *b b* is a smooth depression *g g*, which 30 forms a band between the prisms and the punties and between them and the base of the receptacle.

What I claim, and desire to secure by Letters Patent, is—

The design for a glass receptacle as herein shown and described.

In testimony whereof I have signed my name to this specification, in the presence of two subscribing witnesses, on this 25th day 40 of July, 1901.

ANDREW SNOW, JR.
